UNITED STATES PATENT OFFICE.

WILLIAM N. PILKINGTON, OF ST. HELENS, ENGLAND, ASSIGNOR TO PILKINGTON BROTHERS LIMITED, OF ST. HELENS, ENGLAND.

DESIGN FOR SHEET GLASS.

Application filed January 6, 1923. Serial No. 4,823. Term of patent 14 years.

To all whom it may concern:

Be it known that I, WILLIAM NORMAN PILKINGTON, subject of the King of Great Britain, residing at St. Helens, in the county of Lancaster, England, have invented a new, original, and ornamental Design for Sheet Glass, of which the following is a specification, reference being had to the accompanying drawing, forming a part thereof.

The design consists of a combination made

up of by a repetition of one flower so arranged as to make a floral design on sheet glass to which it is to be applied.

I claim:—

The ornamental design for sheet glass as shown.

W. N. PILKINGTON.
